CHARLES E. LANG, OF SEBASTAPOL, CALIFORNIA.

FOOT-REST AND SHOE-CLAMP.

1,073,807.

Specification of Letters Patent. Patented Sept. 23, 1913.

Application filed July 29, 1912. Serial No. 711,987.

To all whom it may concern:

Be it known that I, CHARLES E. LANG, a citizen of the United States, residing at Sebastopol, in the county of Sonoma and 5 State of California, have invented new and useful Improvements in Foot-Rests and Shoe-Clamps, of which the following is a specification.

This invention relates to a foot rest and 10 shoe clamp.

It is the object of this invention to provide a foot rest and shoe clamp for use on shoe-blacking stands for securely holding the shoe against movement while it is being 15 blackened and polished.

Another object is to provide a device of the above character which is simple in construction and operation, and which is so constructed that the shoe may be easily and 20 quickly clamped thereon and released therefrom.

The invention resides in a shoe clamping means mounted on a suitable foot rest and means for operating the shoe clamp, by 25 which it may be clamped and locked against shoes of various widths, without necessitating adjustment.

The invention further consists of the parts and the construction and combination of 30 parts as hereinafter more fully described and claimed, having reference to the accompanying drawings, in which—

Figure 1 is a vertical section of the invention, partly in elevation. Fig. 2 is a plan 35 view with parts broken away.

In the drawings A represents the sole supporting portion of the device which is preferably formed of cast metal. The sole support A is in the form of a plate, and is 40 designed to be mounted on a standard 2, of any suitable description. Downwardly projecting flanges 3 are formed on the outer edges of the sole support A, and extending on opposite sides of the standard 2 are se- 45 cured thereto by means of bolts 4. Formed integral with the sole support A is a heel rest 5, which consists of a horizontal projecting shelf or flange carried on a trans- 50 verse vertical wall 6, extending between the flanges 3. The upper end of the wall 6 terminates in a transverse rib or flange 7, which 55 extends above the face of the sole support A and is designed to engage a shoe at the point of juncture between the heel and sole there- of. The sole support A, flanges 3, wall 6,

rib 7, and the heel support 5 are preferably cast to form an integral structure. Mounted on the wall 6 beneath the sole supporting plate A is a horizontally extending bracket 8 formed with a horizontal longitudinally 60 extending slot 9, adjacent its outer end. This bracket 8 may be formed integral with the wall 6, or may be connected thereto by screw threads, as shown in Fig. 1. Extending through the slot 9 and slidably therein, 65 in a pin 10 on which is mounted a lever-arm 11, which arms is designed to be rocked in relation to the bracket 8 with the pin 10 as a fulcrum. Wound on the bracket 8 and bearing between the wall 6 and the lever- 70 arm 11, is a helical spring 12 which is tensioned to bear between the wall 6 and the lever-arm 11 in such manner as to normally retain the latter in its outermost position 75 in relation to the bracket 8; the pin 10 bearing against the outer end of the slot 9 to limit the outward movement of the lever- arm 11. Formed on the upper end of the lever-arm 11 is an eccentric cam face 13, which is designed to bear against the spring 80 12 when the lever-arm 11 is rocked in an upward direction as will presently be described.

Pivottally mounted on the upper face of the sole supporting plate A on a pivot pin 85 14 is a pair of sole clamping arms 15, which arms are formed at their outer ends with upwardly and inwardly extending hook-shaped portions 16, which are adapted to engage the outer edges of the shoe soles. 90 The sole clamps 15 are intended to be rocked on their pivot pin 14 so as to throw the members 16 in and out of engagement with the shoe by means of the lever-arm 11, which is connected to the clamps 15 by means of 95 links 17 pivotally connected at one end to the lever-arm 11, and pivotally connected at the other end to downwardly projecting swivels 18 carried by the clamps 15; the swivels 18 extending through perforations 100 or slots 19, formed in the sole supporting plate A, and serving to permit a necessary oscillating movement of the clamps in relation to the links. The clamps 15 are nor- 105 mally retained in their outermost position by reason of the spring 12 bearing against the upper portion of the lever-arm 11; the pressure of the spring 12 tending to rock the lower portion of the lever-arm 11 in an inward direction, which movement is trans- 110

mitted through the links 17 to rock the clamps 15 in an outward direction on the pivot pin 14.

In the operation of the invention the shoe 5 is placed with the sole resting on the plate A and the heel resting on the shelf or flange 5, and engaged on its inner edge by the wall 6 and at its point of juncture with the sole by the rib 7; the upwardly projecting portions 16 on the clamps 15 extending upwardly on opposite sides of the shoe sole. The lever-arm 11 is then rocked in an upward direction on the pivot pin 10, into the position indicated in dotted lines in Fig. 1, 15 thereby causing the clamps 15 to move inwardly by means of the links 17 and drawing the members 16 into engagement with the sole of the shoe. In this operation, the pivotal connection between the links 17 and 20 the lever-arm 11 moves from its normal position below the pivot pin 10 to a point thereabove, so that the spring 12 bearing against the cam face 13 on the upper end of the lever-arm 11 will act to lock the latter 25 in its uppermost position.

It is to be observed that when no opposition is made to the inward movement of the clamps 15, that the lever-arm 11 will swing freely on the pivot 10 from its lowermost to its uppermost position without an appreciable compression of the spring 12; however, when the outer ends of the clamps close against the edges of a shoe sole to limit their inward movement, the pivot pin 30 10 of the lever 11 will move inwardly along the slot 9 in opposition to and compressing the spring 12. The slot 9 thus serves as a means for allowing the fulcrum point or pivot pin 10 of the lever 11 to shift any distance that may be required on the blocking of the clamps 15 to allow the links 17 being swung to their locking position above the pin 10. By this construction the clamps 15 are adapted to engage shoe soles of various 45 widths without necessitating any adjustment of the lever 11 other than the automatic shifting of its fulcrum.

From the foregoing it will be seen that when it is desired to clamp a shoe to the sole support A, it is only necessary to rock the lever 11 from its lowermost to its uppermost position, and that when it is desired to release the shoe, the lever 11 will be rocked from its uppermost to its lowermost position; the spring 12 acting to normally retain the lever in either position.

Having thus described my invention, what I claim and desire to secure by Letters Patent, is—

60 1. In a foot rest and shoe clamp, the com-

bination of a shoe supporting member, a sole engaging clamp thereon, a hand-lever, and means including a resilient spring coöperating with said lever for operating the clamp by the lever whereby the clamp can be closed 65 and locked against shoe-soles of various widths.

2. In a foot rest and shoe clamp, the combination of a shoe supporting member, a sole engaging clamp thereon, consisting of a pair 70 of coöperating jaw-members pivoted on the shoe support, a link connected to each of the jaw-members, a lever to which the links are connected, and means including a sliding pivot for said lever for locking the lever 75 in either of two positions to retain the clamp in or out of engagement with a shoe.

3. In a foot rest and shoe clamp, the combination of a shoe supporting member, a sole engaging clamp thereon, consisting of a pair 80 of coöperating jaw-members pivoted on the shoe support, a link connected to each of the jaw-members, a lever to which the links are connected, means including a shifting fulcrum for said lever for locking the lever in 85 either of two positions to retain the clamp in or out of engagement with a shoe, and resilient means whereby the clamp can be closed and locked against shoe-soles of various 90 widths by the operation of the lever.

4. In a foot rest and shoe clamp, the combination with a shoe supporting member, of a pair of coöperating jaw-members pivoted on the shoe support, a swivel carried by each jaw-member, a link attached to each swivel, 95 a lever-arm to which the links are connected, said lever-arm having a shiftable fulcrum, and means for locking the lever-arm in either of two positions to retain the jaw-members in or out of engagement with a 100 shoe.

5. In a foot rest and shoe clamp, the combination with a shoe supporting member, of a pair of coöperating jaw-members pivoted on the shoe support, a swivel carried by each 105 jaw-member, a link attached to each swivel, a lever-arm to which the links are connected, a bracket formed with a slot, a pin extending through said slot and movable lengthwise thereof, on which the lever-arm is fulcrumed, and a spring bearing against the lever-arm adjacent the pin to normally retain the lever-arm in either of two positions.

In testimony whereof I have hereunto set my hand in the presence of two subscribing 115 witnesses.
